LIONEL WOLFFSOHN, (NOW BY JUDICIAL CHANGE OF NAME LIONEL M. WOOLSON,) OF HOBOKEN, NEW JERSEY, ASSIGNOR, BY MESNE ASSIGNMENTS, TO BIJUR MOTOR APPLIANCE COMPANY, A CORPORATION OF DELAWARE.

IGNITION APPARATUS.

1,279,816.

Specification of Letters Patent. Patented Sept. 24, 1918.

Application filed April 30, 1915. Serial No. 24,846.

To all whom it may concern:

Be it known that I, LIONEL WOLFFSOHN, a citizen of the United States, and residing at Hoboken, in the county of Hudson and State of New Jersey, have invented a new and Improved Ignition Apparatus of which the following specification is a full disclosure.

This invention relates to ignition apparatus for internal combustion engines.

One of the objects thereof is to provide practical apparatus of the above type adapted automatically to meet changing conditions of running with improved uniformity in action. Another object is to provide in ignition apparatus simple and reliable means for reducing undesirable sparking. Another object is to provide ignition apparatus in which the current is economically used under all conditions.

Other objects will be in part obvious and in part pointed out hereinafter.

The invention accordingly consists in the features of construction combinations of elements, and arrangement of parts which will be exemplified in the following description and the scope of the application of which will be indicated in the appended claims.

In the accompanying drawing, in which is shown one or more of various possible embodiments of the several features of this invention, Figure 1 is a diagrammatic plan of one of the same. Fig. 2 is a diagrammatic elevation of driving connections. Fig. 3 is a diagrammatic plan of somewhat different apparatus.

Similar reference characters refer to similar parts throughout the several views of the drawing.

Referring now to Fig. 1 of the drawing, there is indicated at 1 the commutator of an electric generator indicated at 2, this generator being driven from an internal combustion engine and serving to perform the functions hereinafter described. Generator 2 is here indicated as of the four-pole type with cross connected commutator segments, the main brushes being thus spaced about ninety degrees and are indicated at 3 and 4. From these brushes which are substantially at neutral points at the commutator there are led conductors 5 and 6 the former passing to a stationary contact 7 of a reverse current relay or main switch 8. The spring retracted

movable contact 9 of this switch is connected as by conductor 10 with a storage battery 11, the remaining terminal of which passes through the series coil 12 of the switch 8 to join conductor 6. The switch 8 acts in a well-known way to prevent reverse discharge of the battery 11 through the generator when the latter is standing still or running at a slow speed. When, however, the generator speed rises to a predetermined degree, the field of its voltage coil 13 attracts the armature or swinging contact 9 and closes the switch; the coil 8 thereupon acting cumulatively to tend to hold the switch closed until the fall in generator speed results in a tendency to reverse current in the latter coil.

The shunt field winding of the generator is indicated at 14 and has connected in series therewith a resistance element 15 which is normally shunted by a conductor 16, the circuit of which is controlled by the spring retracted contact 17. A generator voltage coil 18, however, is operatively related to the swinging contact 17 and upon the generator speed reaching a high value, the field of coil 18 becomes of such strength that it actuates contact 17 to break the shunt about resistance 15 and thus materially weaken the generator field. This action is repeated with a frequency depending upon the generator speed and thus tends to maintain the voltage of the generator output substantially constant. A low temperature coefficient resistance 18^a is preferably in series with coil 18.

Mounted upon commutator 1 at a point offset from any of the neutral points and spaced, in this case, at about forty degrees from the brush 4, is an auxiliary brush 19. From this brush a conductor 20 leads through the primary coil 21 of an induction coil 22, the secondary 23 of which is adapted to receive a high voltage induced current for the ignition devices diagrammatically indicated at 24. From coil 21 a conductor 25 leads to a circuit interrupting member 26 which, swinging about the axis 27, separates the coacting contacts 28 and thus interrupts the circuit. Member 26 is preferably actuated by a cam 29 coacting with roller 30 upon the swinging arm and driven in a suitable way from the internal combustion engine.

The contacts 28 of the above interrupting

device are bridged about by a condenser 31 and an additional condenser section 32 is connected between the contact member 26 and the field circuit of the generator as at 33. 5 It will thus be seen that the coil 18, with associated parts, tends to regulate the voltage of the output of generator 2, but it may be noted that many of the advantages of this invention are achieved in apparatus in which 10 the generator current is maintained substantially constant and it may also be noted that the term "function" of this current is used herein broadly to denote any characteristic thereof such as either its voltage or current 15 value. Terms of the nature of "interrupt" are also broadly used herein as descriptive of an action in which the current is so changed as to gain a substantial effect of a cessation, although the circuit is not necessarily completely broken. 20

As shown in Fig. 2 of the drawings, the generator 2 is driven from the internal combustion engine 34 through a coupling 35 so formed as to permit a slight relative angular movement between the shaft sections 34^a and 34^b. This may be accomplished by providing the coupling member 36 with a lug 37 and forming in coupling member 38 a circumferential slot 40 within which the lug 37 is permitted a limited range of movement. The interrupter cam 29 is also driven from engine 34 through the generator 2 as diagrammatically indicated in the drawing.

Considering now the action of the above 35 described apparatus, the generator, being driven from the engine, serves upon its voltage rising to a proper point, to charge the battery 11 in the usual way. The voltage of the generator output, moreover, is regulated 40 by voltage coil 18 which becomes effective with rise of speed of the generator and which breaks the shunt 16 with a frequency varying with the speed so that under conditions of extremely fast running, this shunt 45 is broken a large proportion of the time.

Considering now the ignition apparatus, an ignition circuit is connected as shown between brush 3 and brush 19, it being understood that the term "ignition circuit" is 50 broadly used to denote a circuit in ignition apparatus but not necessarily that in which the spark plugs are positioned. When the switch 8 is open and the hand ignition switch 41 is closed, as in the starting of the 55 engine, the coil 21 is connected across the battery thus giving substantially full battery voltage and resulting in strong ignition current to start the engine under otherwise adverse conditions. If, however, the switch 60 41 be left closed with the engine stopped and with cam 29 in such position as to leave contacts 28 in engagement, then there might be not only a long continued leakage of battery current but a possible heating of certain 65 of the parts through which this current

flows. In the present case, however, the flow of this current is such that it tends to rotate the generator 2 acting as a motor in the direction of drive of the engine 34. A limited range of rotation of the dynamo 70 armature is permitted by the loose connection at 35 and this movement is sufficient to so rotate cam 29 as to move the contacts 28 out of engagement one with another and thus stop the leakage of current. Assuming, 75 however, that the engine is started, and that its speed increases to the point at which switch 8 closes, the ignition circuit will then be supplied from the generator as it is bridged between brushes 80 3 and 19. Assuming the direction of drive of the generator to be that indicated by the arrow in Fig. 1 of the drawing, there is a tendency as the generator speed increases to rotate the neutral points 85 of the magnetic field in this direction, that is, from the brush 4 toward the brush 19. This action, which is due partially to the armature reaction and also, in this case, to the weakening of the field by the regulating apparatus, reduces the potential difference between brushes 4 and 19 and correspondingly increases the voltage between brush 19 and brush 3. This field distortion increases as the speed increases and thus the 90 voltage impressed upon coil 21 also increases as the engine speed increases, without interfering in any way with the regulation of the current fed to battery 11. In this manner, as the engine speeds up and the time 95 of contact of the members 28 becomes more brief, with a consequent tendency to lessen the value which the current in coil 21 attains, this being due to the self-induction of the latter device, there is impressed upon 100 the circuit an increasing voltage which offsets this action and results in approximately uniform ignition current under all conditions of running.

It will also be noted that before the 110 switch 8 is closed, the condenser section 32 is inoperative as it is not bridged either directly or indirectly about contacts 28. At this stage, which corresponds to a slow speed of running, the current in the ignition circuit is slightly lower than with higher generator speeds as the impressed voltage is merely that of the discharge voltage of the battery. When, however, the switch 8 is 115 closed, the current in the ignition circuit is derived from the generator as this action does not occur until the generator voltage predominates over that of the battery. With this condition, it will be seen that the condenser section 32 is added in effect to the condenser section 31 as both are bridged about the contacts 28. The main switch 8 will not close until a certain generator speed has been reached, and as this speed increases to and past such point, the total effective 120 125 130

condensing apparatus about contacts 28 is thus also increased. As the generator speed increases still further, there is, with the present apparatus, a slight tendency to decrease of current in the ignition circuit and as this speed is approached the effect of condenser section 32 is progressively decreased, due to the increasing frequency with which coil 18 breaks the shunt about the 10 resistance element 15. The capacity bridged about the interrupter is thus varied with the engine speed, and I have found that I can thus gain a more effective ignition with a given amount of sparking at the interrupter contacts.

In Fig. 3 of the drawing is shown apparatus in which certain features of this invention are embodied and which comprises a generator, commutator, electric switch and 20 storage battery, substantially as in the apparatus hereinbefore described. The field winding 42, however, is bridged between the brushes 4 and 19 and, due to armature reaction, is automatically weakened as the speed 25 of the generator rises for reasons hereinbefore described. With a proper proportioning of the various coils, this connection of the field will give a constant or drooping charging current of the generator. Here 30 also, as in the apparatus first described, the ignition coil 21 is connected between brushes 3 and 19 and thus its circuit has impressed thereon an automatically increasing voltage as the speed of the generator rises, and all 35 without interference with the substantial constancy of the current output of the generator.

The arrangement for connecting the ignition circuit to derive current from the generator taken by itself is not claimed herein, but is made the subject-matter of my 40 pending application Serial No. 165,307, filed April 30th, 1917, which copending application is a continuation of the present application 45 as to all common subject-matter.

It will thus be seen that there is provided apparatus in which the various objects of this invention are achieved and in which the several advantages hereinbefore noted 50 are gained.

As many changes might be made in the above construction, and as many apparently different embodiments might be made of this invention without departing from the 55 scope thereof, it is intended that all features herein described or shown in the accompanying drawings shall be interpreted as illustrative and not in a limiting sense.

Having thus revealed this invention, I 60 claim as new and desire to secure the following combinations of elements, or equivalents thereof, by Letters Patent of the United States:—

1. In ignition apparatus for internal 65 combustion engines, in combination, an in-

ternal combustion engine, a battery, a generator driven from said engine, an ignition circuit comprising an interrupter driven from said engine and mechanically connected with said generator, connections from 70 said battery to said ignition circuit, and means adapted, upon said battery supplying said ignition circuit with said engine at rest to cause said generator to move as a motor and turn said interrupter to circuit 75 opening position.

2. In ignition apparatus for internal combustion engines, in combination, an internal combustion engine, a generator driven from said engine through a connection 80 adapted to permit a limited range of turning movement of the generator armature with respect to the engine, a battery, an ignition circuit comprising an interrupter driven from said engine through said generator, connections from said battery to said ignition circuit, and means adapted upon 85 said battery supplying said ignition circuit, with said generator at rest to cause said generator to move as a motor independently 90 of said engine and turn said interrupter to circuit opening position.

3. In ignition apparatus for internal combustion engines, in combination, an internal combustion engine, a battery, a generator driven from said engine through a loose connection adapted to permit a limited range of relative movement, an ignition coil, 95 connections between said generator and said battery, and means connecting said ignition coil with said generator and with said battery.

4. In ignition apparatus for internal combustion engines, in combination, an internal combustion engine, a battery, a generator, a brush substantially at a neutral point of the commutator of said generator, a brush spaced from the neutral points of said commutator, an ignition coil, means connecting 100 said ignition coil across said brushes, means adapted to lead current from said battery through one or more armature coils of said generator and through said ignition coil, and a loose mechanical connection through 105 which said generator is driven from said engine.

5. In ignition apparatus for internal combustion engines, in combination, an internal combustion engine, a battery, a generator, a brush substantially at a neutral point of the commutator of said generator, a brush spaced from the neutral points of said commutator, an ignition coil, means connecting 110 said ignition coil across said brushes, means adapted to lead current from said battery through the armature coils of said generator and through said ignition coil, a loose 115 mechanical connection through which said generator is driven from said engine, a third brush substantially at a neutral point of 120

125

130

said commutator, means adapted to connect said battery between said third brush and one of said first brushes, and means adapted to regulate a function of the output of said generator through said last circuit.

6. In ignition apparatus for internal combustion engines, in combination, a circuit comprising an interrupting device, a condenser bridged about said device, and means adapted automatically to change the effective capacity of said condenser as the running conditions of the apparatus change.

7. In ignition apparatus for internal combustion engines, in combination, a circuit comprising an interrupting device, a condenser bridged about said device, and means adapted automatically to change the effective capacity of said condenser in accordance with changes in the value of the voltage impressed on the interruptable circuit.

8. In ignition apparatus for internal combustion engines, in combination, a battery, a generator, an ignition circuit, connections between said ignition circuit and said battery, means adapted to connect said generator with said battery, an interrupting device for said ignition circuit, a condenser bridged about said interrupting device, means adapted to connect said generator with said ignition circuit, and means adapted to decrease the effective capacity of said condenser as the voltage tends to rise with increased speed of said generator.

9. In ignition apparatus for internal combustion engines, in combination, a battery, a generator, an ignition circuit, connections between said ignition circuit and said battery, means adapted to connect said generator with said battery, an interrupting device for said ignition circuit, a condenser bridged about said interrupting device, means adapted to connect said generator with said ignition circuit, means adapted to decrease the effective capacity of said condenser as the speed of said generator increases up to the time when the generator is giving full current in the circuit to said battery, and means adapted automatically to reduce said effective capacity as the speed of said generator increases subsequent to said time.

10. In ignition apparatus for internal combustion engines, in combination, a generator, means adapted to maintain substantially constant a function of the output of said generator as its speed varies, means so connected to said generator as to draw therefrom a current of increasing voltage as the speed of said generator increases, an ignition coil connected with said last means, an interrupting device in the circuit of said ignition coil, a condenser bridged about said interrupting device, and means adapted to de-

crease the effective capacity of said condenser as the voltage tends to rise with increased speed of said generator.

11. In ignition apparatus for internal combustion engines, in combination, a circuit comprising an interrupting device, a condenser bridged about said device, means adapted automatically to change the effective capacity of said condenser in accordance with changes in the value of a characteristic of the energy passing in said interruptable circuit, a generator connected with said circuit, and means adapted to increase the voltage impressed on said circuit as the speed of said generator increases.

12. In ignition apparatus for internal combustion engines, in combination, a circuit comprising an interrupting device, a condenser bridged about said device, means adapted automatically to change the effective capacity of said condenser in accordance with changes in the value of a characteristic of the energy passing in said interruptable circuit, a generator connected with said circuit, means adapted to increase the voltage impressed on said circuit as the speed of said generator increases, a battery, a circuit leading from said generator to said battery, and means adapted to maintain substantially constant a function of the current in said last circuit.

13. In ignition apparatus for internal combustion engines, in combination, an internal combustion engine, a battery, a generator driven from said engine, an ignition circuit comprising an interrupter driven from said engine and mechanically connected with said generator, connections from said battery to said ignition circuit, means adapted, upon said battery supplying said ignition circuit with said engine at rest, to cause said generator to move as a motor and turn said interrupter to circuit opening position, a condenser bridged about said interrupter, and means adapted automatically to change the effective capacity of said condenser as said generator changes speed.

14. In ignition apparatus for internal combustion engines, in combination, a circuit comprising an interrupting device, a spark preventing means bridged about said device and means adapted automatically to vary the effectiveness of said spark preventing means as the running condition of the apparatus changes.

In witness whereof I hereunto subscribe my name as attested by the two subscribing witnesses.

LIONEL WOLFFSOHN.
